Specification for Design.

Patented Aug. 29, 1922.

Application filed May 13, 1921. Serial No. 469,391. Term of patent 14 years.

To all whom it may concern:

Be it known that I, FRANK YOKEL, a citizen of the United States, residing at Hartford, in the county of Hartford and State of Connecticut, have invented a new, original, and ornamental Design for a Lighting Fixture (Case C, No. 11,251), of which the following is a specification, reference being had to the accompanying drawings, forming part thereof.

Fig. 1 is a side elevation;

Fig. 2 is a central vertical section of the lower part of the fixture; and

Fig. 3 is a bottom plan view thereof.

I claim:

The ornamental design for a lighting fixture, as shown.

FRANK YOKEL.
